UNITED STATES PATENT OFFICE.

ANTON PATAKY, OF CONNEAUT, OHIO.

WASHBOARD HOLDER.

1,409,233.

Specification of Letters Patent. Patented Mar. 14, 1922.

Application filed July 28, 1921. Serial No. 488,147.

To all whom it may concern:

Be it known that I, ANTON PATAKY, a citizen of Hungary, residing at Conneaut, in the county of Ashtabula and State of Ohio, 5 have invented certain new and useful Improvements in Washboard Holders, of which the following is a specification.

This invention relates to certain new and useful improvements in wash board holders 10 and has particular reference to a support for a wash board when positioned in a tub.

The primary object of the invention embodies a wash board holder or support wherein a clamping member adapted for attachment to the upper edge of a wash tub has a bracket arm swivelly connected thereto with a wash board secured to the bracket arm in a manner to permit a slight movement of the board relative to the tub so 20 that boards of different lengths may be supported on a tub and capable of movement to cause the feet of the board to engage the bottom of the tub.

With the above general objects in view 25 and others that will appear as the nature of the invention is better understood, the same consists of the novel form, combination and arrangement of parts hereinafter more fully described, shown in the accompanying 30 drawing and claimed.

In the drawing, wherein like reference characters designate corresponding parts throughout the several views,

Figure 1 is a side elevational view partly 35 in section of a wash board holder showing in section a portion of a tub and a wash board,

Figure 2 is a top plan view of the wash board holder,

Figure 3 is a cross sectional view taken 40 on line III—III of Fig. 1 showing the connection between the separable members of the clamp and the connection between one of the members of the clamp and the wash 45 board supporting bracket, and

Figures 4 and 5 are fragmentary perspective views of the two sections of the clamp.

Referring more in detail to the accompanying drawing there is illustrated a wash 50 board holder embodying a clamp formed of a pair of plates 1 and 2 having clamping arms 3 adapted for engagement with the upper beaded or rolled edge 4 of a tub 5.

The clamping plate 1 shown in detail in Fig. 4 embodies a pair of laterally projecting lugs 6 carrying opposed pins 7 while an opening 8 is formed in the plate 1 for purposes presently to appear.

The clamping plate 2 shown more clearly in Fig. 5 embodies a threaded aperture 9 and a block 10 preferably formed integral with the upper end thereof, the block 10 being provided with side recesses 11 and a forward socket 12 in the front face thereof. In assembling the two members of the clamp, 65 the pins 7 of the lugs 6 are received in the sockets 11 and rest upon the bottom walls thereof as clearly shown in Figs. 1 to 3 while a limited screw 13 passes through the opening 8 and the clamping plate 1 threads 70 into the aperture 9 of the clamp plate 2 for securing the jaws 3 upon the upper end of the tub 5 and for retaining the pins 7 in the sockets 11.

The bracket arm for supporting the wash 75 board embodies a rod 14 provided with a ball head 15 upon one end thereof for reception in the recess 12 while the plate 16 received on the rod 14 is secured to the adjacent face of the block 10 by the fastening 80 devices 17 as clearly shown in Figs. 2 and 3.

A plate 18 is suitably secured to the other end of the rod 14 and has an opening 19 adjacent each end thereof for reception of fastening devices 20 whereby the plate 18 85 is secured against the shoulder 21 of the wash board 22.

From the above detail description of the device it is thought that the construction and operation thereof will at once be apparent, it being noted that the clamping plates 1 and 2 are maintained in assembled relations by the screw 13 that also screws the clamping jaws 3 upon the upper end of the tub. The ball and socket connection between the rod 14 and the block 10 as shown in Figs. 1 to 3 will permit the board 22 to move a limited distance within the tub 5 so that tubs and wash boards of various sizes may be used with a standard type of clamp 100 and permit the feet of the board to rest upon the bottom of the tub and thereby constitute a substantial support for the board.

While there is herein shown and described the preferred embodiment of the present invention, it is nevertheless to be understood 105

that minor changes may be made therein without departing from the spirit and scope thereof.

What is claimed as new is:—

- 5 1. A wash board holder comprising a clamp formed of separate plates, a block carried by the upper end of one of the plates and having side sockets therein, pins carried by the other plate for reception in said sockets, a screw for retaining the plates in assembled relation, and a wash board supporting bracket arm carried by said block.
- 10 2. A wash board holder comprising a clamp formed of separate plates, a block carried by the upper end of one of the plates and having side sockets therein, pins carried by the other plate for reception in said sockets, a screw for retaining the plates in assembled relation, and a wash board supporting bracket arm swivelly attached to said block.
- 15 3. A wash board holder comprising a clamp formed of separate plates, a block carried by the upper end of one of the plates and having side sockets therein, pins carried by the other plate for reception in said sockets, a screw for retaining the plates in assembled relation, and a wash board supporting bracket arm swivelly attached to

said block, said arm having a plate carried 30 by the end thereof spaced from the block for supporting the wash board.

4. A wash board holder comprising a pair of clamping plates, a block carried by the upper end of one of the plates and having 35 side pockets therein, a pair of spaced lugs carried by the upper end of the other plate, an inwardly directed pin carried by each lug adapted for reception in the block sockets, clamping jaws carried by the lower ends 40 of the clamping plates, a clamping screw detachably connecting the plates, and a wash board supporting the bracket arm connected to said block.

5. A wash board holder comprising a pair 45 of clamping plates, a block carried by the upper end of one of the plates, a pair of spaced lugs carried by the upper end of the other plate, an inwardly directed pin carried by each lug adapted for reception in 50 the block sockets, clamping jaws carried by the lower ends of the clamping plates, a clamping screw detachably connecting the plates, and a wash board supporting bracket arm swivelly connected to said block. 55

In testimony whereof I affix my signature.

ANTON PATAKY.
